UNITED STATES PATENT OFFICE.

THOMAS NATHAN RUSSELL, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

CAR CONSTRUCTION.

1,385,399.

Specification of Letters Patent. Patented July 26, 1921.

Original application filed January 26, 1914, Serial No. 814,519. Divided and this application filed May 27, 1918. Serial No. 236,741.

To all whom it may concern:

Be it known that I, THOMAS NATHAN RUSSELL, a citizen of the United States, and a resident of Chicago, in the State of Illinois, have invented certain new and useful improvements in Car Construction, of which the following is a specification.

My present invention relates in general to car construction, and more particularly 10 to the bodies thereof, and has special reference to improvements in the framing of such bodies.

The principal objects of my present invention are the provision of a body construction involving the use of metallic members, wherein a given weight of metal is most advantageously employed in the production of a body of maximum rigidity and strength, a minimum of weight, simplicity 20 of manufacture, avoidance of waste of material, and low cost; the provision of an improved arrangement of end post construction; the provision of an improved carline construction which is adaptable for employment as a component part of a composite end plate construction; the provision of improved means for securing the posts to the end plate, and the end plate in turn to the other members of the car framing, in order 25 to secure the greatest strength and rigidity of the frame and roof construction, and attain the greatest resistance to all bending moments and other stresses, together with such other objects as may hereinafter appear.

Certain constructions involving in part my present improvements are shown in my co-pending application for Letters Patent, Serial No. 814,519, filed January 26, 1914, 30 of which the present application is a division.

In attaining the foregoing objects, and certain additional advantages to be below disclosed, I have provided the construction 35 illustrated in the accompanying drawings, wherein—

Figure 1 is a perspective view of a portion of a car framing embodying my present improvements;

50 Fig. 2 is an end view of a car body employing the framing of Fig. 1, the outer sheathing being partially removed and certain of the parts being shown in section.

Fig. 3 is a fragmentary longitudinal sectional view of the structure of Fig. 2; 55

Figs. 4 and 5 are transverse sectional views of said plate taken on the lines 4—4 and 5—5 of Fig. 2;

Fig. 6 is a plan view of the composite end plate structure; 60

Fig. 7 is a plan view of the blank from which the carline is manufactured;

Fig. 8 is a perspective view of the carline before the filler block is placed in position to form the composite end plate structure; 65

Fig. 9 is a fragmentary longitudinal view, partly in vertical section, of the upper right hand corner of the structure of Fig. 1, illustrative of the manner of attaching the end posts to the composite end plate structure; 70 and

Fig. 10 is a sectional view taken on the line 10—10 of Fig. 9.

Referring first more particularly to Fig. 1 of the drawings, it will be noted that I have here shown a car framing and body employing side sills 10—10, center sills 11, 11, intermediate sills 12, 12, an end sill 13, corner posts 14, 14, counter braces 15, 15, side posts 16, 16, side plates 17, 17, and purlins 18, 18, 80 the construction thus far described being a common one in the art of car construction, the purlins 18 being supported at their ends by end plates 19, and intermediately by carlines 20, both of special construction, which 85 I will proceed to discuss more fully in connection with Figs. 2, and 4 to 8, and said end plates being in turn supported in part by the end posts 21, which I will proceed to discuss more fully in connection with Figs. 90 2, 3, 9 and 10.

In manufacturing the carlines 20, embodying my present improvements, I preferably employ a flat rectangular piece 30 (Fig. 7) 95 of sheet or plate metal, or similar suitable material, and press outwardly oppositely inclined flanged portions 31, 32, by bending the sheet along the line indicated at 33 until the portions 31, 32 assume a position at substantially a right angle to the horizontal plane of the strip, the oppositely inclined flanges 31, 32 forming what for the purpose of convenience I will term the compression portion of the carline or end plate, simultaneously pressing outwardly in the opposite 100 direction from such plane as oppositely in-

clined tension portions, flanges 34 and 35 (which may be seen on inspection of Figs. 2, and 6 to 8), which last named tension portions are formed by bending the sheet 5 along the line indicated at 36, and simultaneously giving the web 37 thus formed the reversely curved S or Z section clearly to be seen on viewing Figs. 4 and 5. The carline 20 of said figures and the composite end 10 plate 19 are of substantially the same construction, save that the composite end plate supports a filler-block indicated at 19^a.

By the employment of suitable dies, cut-outs may be made as indicated at 39, 39, for 15 the formation of brackets 40, 40 (see Figs. 1 and 2), adapted to bear against the side plates 17, 17, and of hangers when secured in position, as by bolts 41, 41, bracing the end plates or carlines against horizontal or 20 rocking movement relatively to the side plates 17, 17, the formation of said brackets 40—40 leaving outwardly projecting hangers 42—42 by means of which the carline 22 may be suspended from the plates 17, 25 bolts 43 (Fig. 1) being conveniently employed for securing the carline in predetermined position.

As will be apparent on inspection of Figs. 2 and 6, the formation of my improved end 30 plate or carline by the method just described will provide oppositely inclined compression surfaces 31, 32, gradually increasing in width from the center of the end plate 19 toward the ends thereof, and thereby 35 giving a maximum width to the projecting hanger portions 42, 42, whereby an additional bracing effect against horizontal strains may be attained, the method referred to further providing tension surfaces 34 and 40 35 which taper from the center of the carline toward the end thereof, thereby affording a maximum amount of material for the formation of the brackets 40, 40.

On viewing Fig. 2 it will be observed 45 that for the purpose of bringing the ends of the roof sheathing directly down upon the ends of the carlines, that is, upon the hangers 42 thereof, and thereby when intermediate purlins 18 are employed, avoiding the 50 necessity of using filler-blocks at such ends, I provide the carlines with bends, as indicated at 44^a, 44^a, whereby the principal advantages of my present construction are all 55 retained, but the roof construction is somewhat simplified.

On viewing Figs. 4 and 5 it will be observed that the compression surfaces 31 and tension surfaces 35 are preferably extended in opposite directions relatively to the 60 curved web 37, this affording a rest or support for the filler-block 19^a of the end plate 19, as is clearly to be seen from inspection of such figures.

Referring now more particularly to Figs. 65 1 and 3, it will be observed that the end posts

21 are preferably of I-beam construction, the surfaces of the web 44 thereof being disposed in a plane parallel to the longitudinal axis of the car, instead of transverse thereof, as is the common practice, the outer ends of such web being cut away from the flanges and bent at a right angle to the body of such web, as indicated at 45, whereby they may be attached to the end sill 13 (Fig. 1) and the composite end plate structure 19, 70 (Figs. 9 and 10), the outer flange 46 being cut away and the inner flange 47 bent at a right angle to the body thereof, as indicated at 48 (Fig. 1), whereby it likewise may be attached to the end sill 13 and the composite 75 end plate structure 19.

The structure just described is advantageous in the following respects, viz.: by the disposition of the web in the manner indicated a greater resistance to bending strains 80 is attained than when the web is arranged transversely of the axis of the car. Furthermore nailing blocks 50, 50 may be inset between the opposed flanges 46, 47 (see Fig. 3) and held in position by intermediate braces 90 51, 51 nailed thereto, as indicated at 52, 52 (see Fig. 2), such nailing blocks 50, 50 forming bases to which the outer sheathing 53 and inner sheeting 54 may be nailed as 95 shown.

Further reference to Fig. 1, it will be observed that the opposite end plate structure 19 is secured by means of tie members 35^a, 35^b to the roof carline 20 which is arranged immediately to the rear of the end of the car. 100 Such arrangement further serving to secure the end plate construction in place and prevent it from dislodgement therefrom in the event of severe shock. The carline 20 and the diagonal members 35^a, 35^b form in effect 105 an interior triangular truss frame secured at one corner to the midportion of said end plate or member 19, and at the other corners to said side plates. Each diagonal member 35^a forms with the adjacent tie member 35^b 110 a frame forming a bracing structure between the end plate or member 19 and the carline 20.

Having thus described my invention and illustrated its use, what I claim as new and 115 desire to secure by Letters Patent is:

1. A car framing construction comprising the combination with longitudinal side plates, a transverse end plate, and a carline, of a unitary structure for bracing the car and 120 having a diagonal member attached at one end to said end plate and at the other end to said carline and a member substantially parallel to said side plates connected at one end to said carline and at the other end to said 125 end plate.

2. A car framing construction comprising the combination with longitudinal side plates, and a transverse end plate of a substantially triangular unitary truss frame 130

connected at one corner to the mid-portion of said end plate and at the other corners to said side plates to brace the car end.

3. A car framing construction comprising
5 the combination with longitudinal side plates, and a transverse end plate of a substantially triangular truss frame connected at one corner to the mid-portion of said end plate, and at the other corners to said side plates, and members substantially parallel
10 to said side plates, each connected at one end to said frame and at the other end to said end plate.

4. A car framing construction comprising
15 the combination with longitudinal side plates, a transverse end plate, and a carline, of a pair of diagonal members each attached at one end adjacent to the mid-point of said end plate and at the other end to said carline,

and a pair of members substantially parallel 20 to said side plates each connected at one end to said end plate and at the other end to said carline adjacent to the point of attachment of said diagonal members.

5. A car framing construction comprising 25 the combination with the longitudinal side plates and the transverse exterior end member of a car body, of an interior truss frame connected to the exterior end member and to the longitudinal side plates for strength- 30 ening the car roof end.

In testimony whereof I have hereunto signed my name in the presence of the two subscribing witnesses.

THOMAS NATHAN RUSSELL.
